UNITED STATES PATENT OFFICE.

NOVIA S. BEAVERS, OF WOODLAND, IOWA.

GASOLENE PRESSURE-LAMP.

No. 868,962.

Specification of Letters Patent.

Patented Oct. 22, 1907.

Application filed June 6, 1904, Serial No. 211,803. Renewed April 24, 1907. Serial No. 370,001.

To all whom it may concern:

Be it known that I, NOVIA S. BEAVERS, a citizen of the United States, residing at Woodland, in the county of Decatur and the State of Iowa, have invented a new 5 and useful Improvement in a Device Adapted to be Used with Gasolene Pressure-Lamps.

The aim of my invention is to provide a mechanism, so arranged that there will be a visible signal given when the reservoir is about to become emptied, and 10 my invention embodies certain other arrangements, of parts, as will be described more fully hereinafter.

In the accompanying drawings, I have shown in Figure 1, an elevation of a system of gasolene lamps arranged in conjunction with my pressure-providing 15 mechanism. Fig. 2 shows an end view of one of the standards, while: Fig. 3 shows a top view of the platform, with portions removed.

In carrying out the aim of my invention, I provide two similar standards, 1 and 2, provided with the foot 20 bars 4, as shown in Fig. 2. These standards, 1 and 2, above are connected by means of the top bar 3, from which depends a hanger 6, as shown in Fig. 1. Pivotal secured to the hanger 6 by means of the pin 7, is the beam 8, provided with the adjustable counter- 25 poise 9, provided with the set screw 10. Also extending from this pivotally held beam 8, is a flag a, while pendent from the opposite end of the beam 8, are a plurality of supporting chains 12, secured to the platform 13, as shown in Fig. 1. Held upon this platform 13, is 30 a gasolene tank A, from which extends a pressure gage 14 and a supply pipe 25, as shown. Connected with this pressure tank, by means of the pipe 15, is an ordinary air pump 17, operated by means of the handle 18, and positioned within the pipe 15, is the valve 16. Po- 35 sitioned adjacent to this gasolene tank A, is a filling tank B, which is connected to the gasolene tank A by means of the two tubes 20 which are each provided with a valve b, as disclosed in Fig. 1. This filling tank B is provided with a filling opening, closed by means of the 40 plug 19, as shown, and through this filling opening, the gasolene is filled into the filling tank B. In filling the tank B, the valves b are closed. As the tank B is of a capacity less than the tank A, this pressure tank A cannot be filled too full of gasolene.

45 Secured to the pipe 26, connected to the supply pipe 25 and to the pressure tank A, are a plurality of gaso- lenes lamps 30 of any approved make or construction,

which lamps 30 are provided with the usual opening and closing valve o.

In referring to Fig. 1, it will be seen that the supply 50 pipe 25 and the pipe 26 are connected by means of the pipe coil 25'.

In Fig. 3 a top view is disclosed with portions removed, showing the relative position of the tanks A and B.

Now, the aim of my invention, is to provide a system of ordinary gasolene pressure lamps with a simple mechanism adapted to supplying the gas to the lamps. In my invention, this is accomplished in first filling the tank B and then allowing the gasolene to escape into 60 the pressure tank A, and the valve 16 is then opened when the pump is operated to provide the required pressure within the tank A. Now, this platform 13 is adapted to swing up and down in the manner of a scale and the counterpoise 9 is so adjusted that when the 65 tank B is full, the platform 13 will rest upon the floor or ground, in which condition, the flag a is a considerable distance above the top bar 3. Now, as the gaso- lenes within the tanks is consumed, the platform 13 is finally over-balanced and rises and the flag a moves 70 downward, below the top bar 3, and so indicate that the tanks need refilling, which is accomplished in cutting off the air from the tank A by means of the valves b. It is, of course, understood that these tanks are made of various sizes and if desired, the filling tank B 75 might be dispensed with, though I prefer using the same.

Having thus described my invention, what I claim as new, and desire to secure by United States Letters Patent is:—

In a device of the character described, the combination with a suitable frame, of a beam pivotally held by said frame, a platform secured to said beam, a gasolene tank upon said platform, a supply pipe extending from said tank, a plurality of vapor lamps, a coil pipe adapted to be 85 lengthened or shortened connected to said gasolene tank, a pump secured to said gasolene tank, a counter-balance secured to said beam, and a signal on said beam, all arranged so that the platform will rise as the gasolene is consumed and will give a signal, substantially in the manner set 90 forth.

In testimony whereof I affix my signature in presence of two witnesses.

NOVIA S. BEAVERS.
